UNITED STATES PATENT OFFICE.

ALBERT T. MATTHEWS, OF THOMASTON, GEORGIA.

RING-LUBRICATING MEANS FOR SPINNING AND TWISTING FRAMES.

Application filed January 14, 1927. Serial No. 161,083.

This invention pertains to ring twisting or spinning frames employed in the textile industry for the preparation of yarns and threads and relates more particularly to means for automatically lubricating the rings and travelers of such a frame.

Various arrangements have heretofore been proposed for lubricating the ring and traveler, most of which either necessitate the use of rings of special and oftentimes expensive construction or provide so inadequate a supply of lubricant that they must be given almost constant attention.

Of recent years the tendency has been to increase the speed of the twisting or spinning spindle and the high speeds now employed make the problem of lubrication of the ring and traveler very important. In accordance with the present invention, I so effectively lubricate the ring and its traveler that an increase of as much as 30% above the normal spindle speed is obtainable without appreciably increasing the temperature of the ring and traveler and I obtain this result without discarding the rings of ordinary type, with which existing machines may be provided, since it requires but slight expense to adapt such rings for the purpose of the present invention.

Moreover, in accordance with my invention the attendance cost, for insuring proper lubrication, is reduced to a minimum.

In the accompanying drawings I have illustrated a preferred embodiment of the present invention and in the drawings,

Fig. 1 is a fragmentary plan view of one end of a ring rail having the present invention incorporated therein;

Fig. 2 is a vertical section substantially on the line 2—2 of Fig. 1; and

Fig. 3 is a fragmentary plan view illustrating a slight modification.

The present invention may be considered to constitute an improvement over the arrangement disclosed in the expired patent to Carter No. 355,506, January 14, 1887. In the patented device the attempt was made to provide lubrication for the traveler and ring without substantially modifying the ring but in accordance with this patented arrangement the reservoir for the oil is of such limited capacity that almost constant care on the part of the attendant is necessary to insure proper lubrication. Furthermore, the wick α , which in the Carter device constitutes the reservoir, is exposed at the front

face of the ring rail so that the lubricant tends to flow outwardly along the front edge of the rail to the same extent that it tends to flow inwardly toward the interior of the ring and thus substantially one-half of the oil supplied is wasted. Moreover, this waste oil flowing over the front face of the rail produces an accumulation of lint and dust which must frequently be removed.

In accordance with the present invention I provide a reservoir of large capacity and having but a single outlet so that all of the oil is usefully employed.

Referring to the drawings, the numeral 1 designates the ring rail which may be of any usual type and this rail is provided with a plurality of spaced openings of which one only is illustrated, this opening being designated by the numeral 2. These openings in the ring rail are adapted to receive the twisting or spinning rings, such a ring 3 being here shown as seated in the opening 2 and removably secured in position by means of the usual set screw 3^a. The ring 3 carries the traveler 4 which may be of usual construction and which is adapted to revolve about the ring under the action of the thread. While I have shown but a single traveler on the ring, I may, if desired, and as is common for certain purposes, provide a plurality of such travelers, this forming no part of the present invention.

In accordance with the present invention I provide a chamber 5 of large capacity as compared with prior constructions of like purpose. This chamber extends downwardly from the upper surface of the rail into the substance of the latter to a suitable depth, and is conveniently formed by drilling a hole downwardly into the rail, using a drill of the proper diameter as here illustrated of the order of one half inch, but stopping the operation before the drill breaks through the under surface of the rail.

I now provide a passage 6 extending from the opening 2 laterally through the substance of the rail into the chamber 5. This passage may conveniently be formed by drilling from the wall of the opening 2 outwardly and this passage is of relatively small diameter as compared with the diameter of the chamber 5.

The ring 3 may be an ordinary ring of usual type and to adapt this ring for use in accordance with the present invention, I merely drill a channel or passage 7, prefer-

ably radially, through the thickness of the ring, and in setting the ring in the rail I cause this passage or channel 7 to register with the passage 6, the diameter of the passages 6 and 7 preferably being substantially alike.

I now arrange a mass of oil-absorbent material 8 within the chamber 5 and preferably extend a portion of this oil-absorbent material inwardly through passages 6 and 7, as shown at 9, terminating the inner end of this absorbent material substantially flush, as shown at 10, with the inner surface of the ring 3. However, the end 10 is so close to the path of the traveler 4 as the latter moves about the circumference of the ring, that oil in minute amounts is transferred to the surface of the traveler each time the latter passes the end 10 of the absorbent material.

Preferably I arrange this absorbent material in the form of a wick, for example, a piece of soft slubbing, roving or woolen yarn having a diameter substantially like that of the passage 6 and having its main part coiled or otherwise disposed within the chamber 5.

While I have shown the passages 6 and 7 as substantially horizontal and radial with respect to the ring 3, I contemplate that these passages may be inclined either upwardly or downwardly or, if desired, may extend in a direction which is not in a radial plane of the ring 3, and I further contemplate that while the chamber 5 may, as above described, be formed conveniently by the use of a drill and thus have a circular contour, it may be formed in other ways and be shaped in any manner desired.

The chamber 5 may be supplied with oil which is absorbed by the wick 8 and which moves along the latter by capillary attraction, assisted by gravity, so that the inner end of the wick is constantly moistened with lubricant and furnishes a very small quantity of lubricant to the traveler at each passage of the latter across the end of the wick. As the chamber 5 has no other outlet than the passage 6, it is impossible for the lubri-

cant to escape at undesired points so that all of the lubricant is usefully employed and is not wasted upon the outer surface of the machine. The chamber 5, as above stated, is of large capacity as compared with the diameter of the passage 6 so that it may furnish lubricant for a relatively long period of use; thus the attendant may supply oil to the machine at the beginning of the day's work and the oil supply thus furnished may be depended upon to last through the day and even longer, provided the chamber 5 be of the relative size here illustrated, or larger.

In the arrangement shown in Fig. 3, the rail 1^a has the chamber 5^a as in the arrangement previously described, but this chamber has two passages 6^a and 6^b leading to the inner surface of ring, and the wick 8^a is so arranged that its opposite ends are disposed within the respective passages 6^a and 6^b.

I claim:

A ring rail having a ring receiving opening, a ring of substantially usual type seated in the opening, and a traveler mounted on the ring, the rail having an oil receiving chamber adapted to receive a substantial coil of wick material and extending downwardly into its substance from its upper face at a point intermediate the ring receiving opening and the front edge of the rail, the wall of the chamber being imperforate at the side opposite to the ring, said chamber having an outlet passage extending horizontally from its lower part to the ring receiving opening, the ring having a passage aligned with the passage in the rail and extending to the inner surface of the ring, the chamber in the rail extending below the passage in the rail and being of a capacity sufficient to hold oil for lubricating the ring and traveler throughout at least one doff or change of bobbins, and an oil absorbent wick having a relatively large portion disposed in said chamber and a relatively small portion extending through the aligned passages in the rail and ring to the inner surface of the ring.

Signed by me at Thomaston, Ga., this 3rd day of January 1927.

ALBERT T. MATTHEWS.
